UNITED STATES PATENT OFFICE.

JAMES EDWARD DAVIDSON AND CURTIS HOLLAND, OF BUTTE, MONTANA.

ELECTRICALLY-OPERATED VALVE.

1,307,899.

Specification of Letters Patent. Patented June 24, 1919.

Application filed October 18, 1916. Serial No. 126,435.

To all whom it may concern:

Be it known that we, JAMES E. DAVIDSON and CURTIS HOLLAND, citizens of the United States, and residents of Butte, in the county 5 of Silverbow and State of Montana, have made certain new and useful Improvements in Electrically-Operated Valves, of which the following is a specification.

Our invention relates generally to valves, 10 more specifically to that type of valves having self-contained electrical mechanism adapted to be operated by an electrical current from a distance, and it consists in the combinations, constructions and arrangements hereinafter described and claimed.

An object of our invention is to provide a service valve arranged to be installed in a pipe line at the required places, and including a closing mechanism which is adapted to 20 be operated by an electrical current from a distance.

Another object of the invention is to provide a valve, as described, which includes an indicating mechanism at the place from 25 which the valve is to be operated, the position of the closing member of the valve being thereby ascertainable by the operator.

Other objects and advantages of the invention will be brought out in the following 30 specification, reference being had to the accompanying drawing forming a part thereof, in which:—

Figure 1 is a perspective view of the valve illustrating more particularly the switch 35 board mechanism, the valve at this position being closed.

Fig. 2 is a rear view of the valve operating and indicating device, Figs. 1 and 2 being read together at the lines *a—b*.

Fig. 3 is a diagrammatic view illustrating the connections between the valve and the distantly located actuating mechanism.

Fig. 4 is a perspective view of the valve, the cover plate being removed.

Fig. 5 is a horizontal section on the line 45 5—5 of Fig. 4, parts being in elevation.

Fig. 6 is a perspective view of the brush arm.

Fig. 7 is a detail perspective view of the brush.

Fig. 8 is a perspective view of the valve viewed from a position opposite to that of Fig. 1.

Fig. 9 is a vertical cross section on the line 55 9—9 of Fig. 8.

Fig. 10 is a cross-section on line 10—10 of Fig. 9.

Fig. 11 is a vertical cross-section on line 11—11 of Fig. 9.

Fig. 12 is a rear elevation of the terminal 60 board showing the connection of the inner terminal ring.

Fig. 13 is a vertical section on line 13—13 of Fig. 5.

Fig. 14 is a detail cross section on the line 65 14—14 of Fig. 10.

In carrying out our invention we provide a bracket 1, which is arranged to be secured to the service valve 2, as indicated clearly in Figs. 5 and 8. The bracket 1 includes a 70 downwardly extending spider 3, at its front end, and secured to the spider 3 is a terminal board 4. The terminal board 4 is constructed of insulating fiber or any other suitable similar material, and is provided with a 75 circular opening 5, disposed substantially in the center of the board. The opening 5 merges at one side with a rectangular opening 6, which is provided for a purpose presently to be explained. 80

Secured to the front face of the terminal board 4, as shown in Fig. 1, is an inner terminal ring 7, which has a laterally extending tongue 8, which, when the switch board is assembled, is bent backwardly through the 85 opening 6, and is secured to the back of the terminal board, as shown in Figs. 10 and 12. Arranged coaxially with the inner terminal ring 7 and secured to the board 4, is a terminal ring consisting of a pair of segments 9 90 and 10. Each of the segments 9 and 10 has an extended ear 9^a and 10^a respectively, to which certain of the circuit wires are connected, as will be presently explained.

Projecting through the opening 5 of the 95 terminal board 4 is a shaft 11. The shaft 11 carries at its outer end, a brush arm 12. By reference to Fig. 14 it will be seen that the brush arm 12 is insulated from the shaft 11 by a brush arm insulator 13 and a brush arm 100 insulating washer 14. The base of the brush arm is provided with a suitable aperture into which the washer 14 is fitted, as shown in Fig. 14, a securing screw clamping the insulating washers to the end of the shaft 11. 105 Disposed at the end of the brush arm 12 is a commutator brush 15, which is provided at its end with a plurality of contact fingers 15^a, which engage the terminal ring 7 and segments 9 and 10, as shown in Fig. 1. As 110

the shaft 11 is rotated the brush arm 12 will move and convey the brush 15 over the terminal rings for a purpose to be presently more fully explained.

- 5 The shaft 11 is rotated by a pawl 16, which engages a ratchet 17 secured to the shaft 11, as shown in Fig. 10. Disposed at either side of the ratchet 17 is a driving arm 18. The driving arms are loosely mounted on 10 the shaft and extend laterally and rest on a heel 19, which is formed integrally with the spider 3. Disposed at the end of the driving arms 18 is a fulcrum pin 20 on which the pawl 16 is mounted. The pawl 16 is retained in engagement with the teeth of the ratchet 17 by a tension spring 21, the spring being suitably secured between the driving arms 18 and to the pawl 16, as shown in Fig. 9. Joined to the fulcrum pin 20 is 15 a link 22. The link 22 at its other end is pivoted to the lower end of a solenoid magnet core 23. The core 23 is composed of laminations of annealed sheet iron, and riveted, as shown, a core of this construction 20 offering better conductivity to the lines of force. The core 23 reciprocates within the coil of a solenoid magnet 24, and as the coil is energized the core 23 will be drawn inwardly, moving the driving arms 18 upwardly and rotating the ratchet 17 a portion 25 of a revolution in a counter clockwise direction, as indicated in Fig. 9. The repeated energization of the coil 24 and consequently the repeated reciprocation of the core 23 will 30 cause ratchet 17 to be rotated step by step and the shaft 11 rotated in consequence. The spool of the solenoid magnet is provided at the top with an adjustable stop 25. The inward thrust of the core 23 may be 35 regulated by adjusting the stop 25 to the desired position. In practice the stop 25 will be situated such a distance from the end of the core 23 when the latter is in its normal position, as will insure the movement of the ratchet 17 the distance of one tooth, when 40 the core 23 is attracted. The solenoid magnet 24 is mounted on the bracket 1, and is secured thereto by suitable screws as shown in Fig. 11.
- 45 The shaft 11 extends into the body of the valve 2, through a suitable stuffing gland 26 and is suitably journaled in the body of the valve as shown in Fig. 5. The shaft 11 carries a fixed pinion 27, which meshes with a gear valve 28. The gear valve 28 is mounted 50 on a stud 29, which is screwed as at 30 into the web 31 of the valve. The web 31 is provided with a plurality of segmental openings 32, with which similar openings 33 of the 55 gear valve 28 are adapted to register when the gear valve is rotated, as presently to be explained. The gear valve 28 is retained in water tight engagement with the web 31 by a tension spring 34. The spring 34 is 60 seated in a recess 35 in the gear valve 28,

and bears against the head of the stud 29, as shown in Fig. 5. Access may be had to the interior of the valve for repairing and other purposes, by the removal of the cover plate 36.

70 Arranged at a distance from the valve 2, is the valve actuator and indicator mechanism 37, as shown in Fig. 2. The indicator includes a casing 38, which is provided with a glazed reading opening 39. The positions 75 of an indicating finger 40 may be ascertained through the glazed opening 39, which, for the purpose of determining the location of the gear valve 28, is inscribed with the words "On" and "Off." The indicating finger 40 80 is fulcrumed on a magnet base 42, as at 41, and as will be presently explained, exercises the functions of an armature. The indicating finger 40 is adapted to be attracted by either of a pair of indicating magnets 43 85 and 44.

85 One end of each of the windings of the indicator magnets 43 and 44 is connected in series with one terminal 45 by wires 56 and 56^a of a switch 46, as indicated in Fig. 3. 90 The switch 46 preferably consists of a push button as indicated in Fig. 2. The other terminal 47 of the switch 46 is connected to the positive pole of a source of electrical energy 48 by a wire 49. The other end of the winding of the magnet 43 is connected to the ear 9^a of the segment 9 by a wire 50, while the other end of the winding of the magnet 44 is connected to the ear 10^a of the terminal segment 10 by a wire 51 on the terminal board 4. The board 4 is provided with a terminal 52 to which the wire 53 leading from the negative pole of the source of electrical energy 48 is connected. A wire 54 95 is connected to the terminal 52 on the board 100 4 and to one end of the winding of the solenoid magnet 24. The other end of the winding of the magnet 24 is connected by a wire 55, to the terminal represented by the tongue 8.

105 Having thus described the construction of our invention, the operation thereof is as follows:—

110 Let it be assumed that the openings 32 and 33 are out of registration, as indicated 115 in Fig. 13, the valve at this time being closed. If it is now desired to open the valve or to move the gear valve 28 which will bring the openings 32 and 33 into registration, the push button 46 is pressed and 120 the circuit is closed between the terminals 45 and 47 in Fig. 3. Current now flows from the positive pole of the source of electric energy 48 through the wire 49 to the terminal 47. The current then passes across 125 the switch 46 to the terminal 45, through the wire 56 and around the winding of the magnet 43. From thence the current passes over the wire 50 to the ear 9^a of the segment 9. At this time the brush 15 is in the posi- 130

tion shown in Figs. 1 and 3, indicated "off". The current now passes from the segment 9 through the brush 15, to the inner terminal ring 7, from the ring 7 over the tongue 8 to the terminal 55, and from thence to the windings of the solenoid magnet 24. Current returns to the battery 48 over the wire 54, through terminal 52, and over the wire 53 to the negative pole. A complete circuit 10 being now established, the core 23 of the solenoid magnet 24 is drawn inwardly. The ratchet 17 and the shaft 11 by which the ratchet 17 is carried, is rotated a distance equal to one tooth. A partial rotation of 15 the shaft 11 is imparted to the valve gear 28 through the pinion 27 and the valve is opened a corresponding distance. The brush arm 12 will have also moved a corresponding distance over the ring 7 and segment 9, the brush 15 remaining in contact with these 20 members until a position presently to be referred to, is reached.

The finger pressure is now relieved from the push button 46. Upon pressing the push 25 button 46 again, the passage of the current from the battery 48, and the actuation of the solenoid 24 is repeated. The valve is thus opened wider. The operation attendant upon pressing the push button 46 is 30 repeated until the openings 32 and 33 are in full registration, the valve at this time being open. When the fully open position of the valve is reached the brush 15 will have passed from contact with the switch segment 35 9 to contact with the switch segment 10, this position being indicated in dotted lines in Fig. 3.

Assume the brush 15 to now be in engagement with the switch segment 10. Upon 40 depressing the push button 46 current will pass from the positive pole of the battery 48 over the wire 49, through the switch 46, over the wires 56 and 56^a to the windings of the indicator magnet 44. The current now 45 passes from the indicator magnet 44 over the wire 51, to the ear 10^a of the segment 10. From thence it passes over the brush 15 of the ring 7. The current passes from the ring 7 through the terminal 55 to the 50 windings of the solenoid magnet 24, from thence to the negative pole of the battery 48, as formerly. The solenoid magnet 24 being now energized, the core 23 is drawn inwardly, and a partial rotation of the shaft 55 11 performed in consequence. The valve now begins to close, and will continue to close by such degrees as is represented by the extent of one of the teeth of the ratchet 17, each time the push button switch 46 is subsequently closed.

It has been stated that the current now flows through the windings of the indicator magnet 44, this having occurred at the moment when the brush 15 engages the segment 60 10. The core of the magnet 44 at that mo-

ment attracted the armature of the indicating finger 40, causing the finger to point to the word "On" in the glazed opening 39. The operator now understands that the valve is fully open. The subsequent depressions 70 of the push button switch 46 will cause the valve to gradually close, as has been explained, the brush 15 in the meantime moving upwardly toward the breach in the outer terminal rings. As soon as the brush moves 75 into contact with the segment 9, the current will be shunted from the indicator magnet 44 to the indicator magnet 43 when the push button switch 46 is again depressed. The finger 40 will then return, pointing to the 80 word "Off" and indicate that the valve is closed.

The operation of again opening the valve consists of again intermittently pressing the 85 push button 46 the number of such depressions as observed in practice serving as an index to the position of the valve gear 28 and thus apprizing the operator of the distance that the valve is open.

While the constructions and arrangements 90 of the device are those of a preferred form, it is obvious that various modifications thereof may be made without departing from the spirit of the invention or the scope of the claims.

We claim:

1. In a device of the character described; the combination of a valve body having a valve seat, an axially mounted gear valve on the valve seat, a shaft, a pinion on the 100 shaft in engagement with the gear valve, a ratchet on the shaft, a driving arm mounted on the shaft adjacent to the ratchet, a pawl fulcrumed on the driving arm, a spring joined to the pawl and to the driving arm to hold the pawl in engagement with the ratchet, a link pivoted on the fulcrum pin of the pawl, a solenoid magnet having a core pivoted to the link, said core being composed of laminations, a normally 105 open electrical circuit in series with the solenoid, a source of electrical energy in said circuit, and a switch for closing the circuit thereby attracting the core.

2. In a device as described, the combination of a valve body having a valve seat, a gear valve mounted coaxially of the valve seat, and adapted to be rotated step-by-step in zones from an "off" to an "on" position, a rotatable shaft, a pinion on the shaft 115 for engagement with the gear valve, a solenoid having a core adapted to be reciprocated, connections between the core and the shaft, a normally open electrical circuit in series with the solenoid, a source of electrical energy in the circuit, a terminal ring associated with said valve body, connected in the electrical circuit, segments concentrically disposed of the terminal ring and connected in the electrical circuit, a brush 120 125 130

- carried by and insulated from the shaft, bridging the terminal ring and one of the concentric segments, an indicator in the circuit including an electro-magnet energized by the circuit completed at the bridged ring and segment, and a pointer attracted by said electro-magnet for indicating the "off" zone of rotation of the valve.
3. In a device as described, the combination of the valve body, a rotatable gear valve adapted to move in a zone from a closed to an open position, a shaft for rotating the valve, a solenoid including a core adapted to reciprocate, connections between the core and the shaft, a normally open electric circuit embracing the solenoid in series, a source of electrical energy in the circuit, indicator electro-magnets in the circuit, a terminal board, a terminal ring in circuit with one end of the solenoid, terminal segments disposed concentrically of the terminal ring, each segment being in circuit with one end of the respective indicator electro-magnets, a brush arm on the valve shaft, a brush on the arm for bridging the terminal ring and one of the segments and energizing one of the said electro-magnets, a manually operated switch in said circuit, and a pointer adapted to be attracted by the energized electro-magnets when the switch is closed, to indicate the zone of movement traversed by the valve.
4. In a device as described, a valve body including a valve seat, a gear valve rotatable over the seat, a gear valve actuating shaft projecting out of the valve body, a terminal board having an opening admit-

ting the end of said shaft, a terminal ring on the board surrounding the shaft end, a pair of terminal segments disposed concentrically of the terminal ring, a brush arm carried by and insulated from the end of said shaft, a brush on the arm engaging the terminal ring and one of the segments, a solenoid magnet mounted on the valve body, and pawl and ratchet connections between the solenoid magnet core and said shaft, for rotating said gear valve and brush arm in one direction.

5. In a valve including the valve body, a rotatable valve plate, a bracket secured to the valve body and having a pendent spider, an insulating terminal board secured to the spider, a valve shaft projecting out of the valve body and through the terminal board, a terminal ring on the board surrounding the shaft end, a pair of terminal segments surrounding the terminal ring, a brush arm mounted on the valve shaft, insulating means between the arm and the shaft, a brush carried by the arm including fingers bridging the terminal ring and one of the terminal segments, a ratchet mounted upon the valve shaft behind the spider, driving arm and pawl connections supported on said shaft and engaging the ratchet respectively, a wheel carried by the spider, limiting the movement of the driving arms in one direction, a solenoid magnet mounted upon the bracket, and a core reciprocating in the solenoid magnet and having connection with the driving arms.

JAMES EDWARD DAVIDSON.
CURTIS HOLLAND.
